United States Patent Office.

HENRY C. DE WITT, OF WAUKEGAN, ILLINOIS.

Letters Patent No. 100,270, dated March 1, 1870.

IMPROVEMENT IN VAPOR BURNERS.

The Schedule referred to in these Letters Patent and making part of the same

I, HENRY C. DE WITT, of Waukegan, in the county of Lake, and State of Illinois, have invented certain Improvements in Carbon Gas-Generators and Burners, of which the following is a specification.

The nature of my invention consists in the construction and arrangement of a carbon gas-generator or burner, so that the same may be consolidated in one piece of metal, containing therein the tubes, air-inlet, reservoir, stop-cock, &c., as is hereafter fully described and set forth.

Figure 1 is a vertical section showing the tube leading to the gas-chamber and the tube leading from the gas-chamber to the discharging-jet.

Figure 2 is a cross-section showing the oxygen-chamber and the tubes leading to and from the oxygen-chamber.

Figure 3 is a view through the burning orifice of fig. 2;

Figure 4 is a plan; and

Figure 5 is a view of the thumb-screw.

k is a tube terminating at the top in the cup-shaped funnel-screw *l*.

o is the burner, the lower end of which screws into the cup-nut *l*, from the lower end of which extends up the burner the tube *e* into the gas-chamber *a*.

The gas-chamber *a* can be located on both sides of the tip or burning orifice.

g is the tube leading from the gas-chamber to the end of the nut or screw *d*.

The nut *d* is made hollow, as shown in figs. 2 and 5 *c* is a gas-jet in the nut or screw *d*, and extends into the hollow of the screw.

h is the mixing-chamber.

The operation of my invention is as follows:

The fluid designed to be used is placed in a receptacle higher than the burner, and is connected with the burner by the tube *k*. The oil passes up through the

tube *k*, thence up through the tube *e* and into the gas-chamber *a*.

A small amount of oil at first passes down the small tube *g* out of the jet *c* and into the cup *l*.

A lighted match is applied to the oil in the cup, which soon heats the burner. The chamber *a* becomes heated and the oil therein is converted into gas. It is then pressed down through the tube *g* and out of the jet *c*.

The jet *c* is located in the oxygen-chamber *b*.

This chamber connects with the mixing-chamber *h* directly at the top of the oxygen-chamber.

The gas from the jet *c* passes up through this connection into the mixing-chamber, and as the gas passes into the mixing-chamber, oxygen from the air mingles with it sufficiently to make a perfect and incandescent flame.

The tubes and gas-chamber in the burner above the jet *c* are kept constantly heated, hence a constant supply of gas is afforded for combustion.

What I claim as my invention, and desire to secure by Letters Patent, is—

1. The construction and arrangement of a metallic gas-generator and burner, when the same has combined within it the air-inlet chamber *b*, mixing-chamber *h*, reservoir *a*, tubes *e* and *g*, and thumb or set-screw *d*, in the manner and for the purpose herein described.

2. The combination and arrangement of the thumb or set-screw *d* (containing within it the jet *c*) with the air-inlet-chamber *b* and tube *g*, in the manner and for the purpose herein described.

H. C. DE WITT.
